ORTHOPEDIC APPLIANCE

Cecilia Bailie, Camden, N. J.

Application August 18, 1936, Serial No. 96,607

8 Claims. (Cl. 2—267)

My invention relates to new and useful orthopedic appliances particularly such as are employed in connection with undeveloped shoulders, hollow backs, a fallen abdomen, and other similar malformations or deformities of the body.

One of the objects of this invention is to construct an appliance of the character mentioned from plastic material which will solidify and retain the desired shape.

Another object of the present invention is to make such an appliance by a unique method.

Another object of the invention is to produce an orthopedic appliance from plates or walls fashioned to correspond to the shape of the deformity and the general contour of a person's body in the region of such deformity thereby acting as a filler in the case of a recessed deformity and functioning to support the surrounding parts of the body.

Another object of the invention is to make a hollow appliance from a plastic composition, for example, the material known on the market as "Plastic wood", and to fashion the same for each individual deformity or malformation.

A further object of the present invention is to produce an appliance of the character mentioned by making a mold from the deformity or malformation, then casting plates or walls of the plastic composition on the mold and finally connecting the plates together along and/or adjacent their edges. Such an appliance will be hollow to some extent and may be reinforced by stays and strengthened by fastenings, preferably of the same material as the plates.

A still further object of this invention is to provide an appliance of predetermined shape for use as an abdominal support.

With the above and other objects in view this invention consists of the details of construction and combination of elements hereinafter set forth and then particularly pointed out in the claims.

In order that those skilled in the art to which this invention appertains may understand how to make and use the same, I will describe a construction in detail, referring by numerals to the accompanying drawing, in which:

Fig. 1 is an inner face view of an orthopedic appliance such as is used for supporting weak shoulders or a deformed back of a person's body.

Fig. 2 is a view, partly in elevation and partly in section on the line 2—2 of Fig. 1 with the belt, band or attaching means removed.

Fig. 3 is a view also partly in elevation and partly in section on the line 3—3 of Fig. 1.

Fig. 4 is an enlarged detail sectional view illustrating ways of fastening the plates or walls together.

Fig. 5 is a fragmentary face view of the appli-

ance illustrating one of the ways of joining the plates.

Fig. 6 is an inner face view of an orthopedic appliance embodying my invention and constituting a ptosis pad.

Fig. 7 is a section on the line 7—7 of Fig. 6.

Fig. 8 is an edge view looking at the lower portion of the device as illustrated in Fig. 6.

In carrying out my invention as herein embodied, 10 represents the inner or contact plate or wall which is fashioned to properly fit and cover the total area of the deformity or malformation. An outer plate or wall 11 is shaped, cross sectionally, to what the surface of the body should be over the area of the deformity and the boundary or contour thereof made to match that of the inner or contact plate. These two plates are then secured together along their borders to form a hollow pad and may be additionally fastened by fastening devices 12 and also may be reinforced with stays 13 on the inside of the hollow appliance thus produced.

More particularly the plates 10 and 11 are produced from a suitable plastic composition which is first formed into thin sheets and this may be done in a manner similar to rolling out pie dough or in any other suitable way. These sheets are then formed or cast over shapes or molds, of plaster of Paris or other suitable material, previously made of the deformity or malformation so that the inner plate 10 will be of the same configuration as the deformity or malformation both as to surface and contour, as in Fig. 1, while the outer plate 11 will be shaped to correspond to what the surface of the body should be over the area of the deformity or malformation.

The two plates thus formed are separate elements and are allowed to thoroughly dry and become permanently set. Preferably one of the plates, as 11, Fig. 5, is slightly smaller than the other and its edge is roughened or serrated as at 14 and the inner surface of the other plate contiguous its border is also roughened to assure a bond between the plates and the joining material 15 which in the present instance is the plastic composition. The joint thus formed is smoothed off or finished after the plastic composition has become hard and set. Prior to the time the plates are put together the stays 13, which may be of cork for lightness, are fixed to one of the plates by some of the plastic composition and a quantity of said plastic composition placed on the free ends of the stays or on the other plate in the localities where said stays will contact said other plate so that when the two plates are pressed together bonds 16 will be produced. Where the edges of the plates are to form a butt joint the plastic composition can be placed in overlapping relation to produce a bond such as shown at 17 in Fig. 7 and can be either inside or outside as will

be obvious. During the hardening or drying periods for the bonds and joints, the plates are held together by suitable clamping means.

After the plates are put together countersunk holes 18 are made in both plates and in order that the holes in one plate will be directly opposite those in the other plate said holes are preferably drilled through and through and then countersunk. Some of the plastic material is next rolled 10 into cylindrical sections and inserted in the countersunk holes and squeezed until heads are produced which fill said countersunk holes thus producing, in effect, rivets with enlarged or bulged bodies.

Finally vent holes 19 are made in both plates to permit circulation of air for causing evaporation of perspiration and keeping the appliance cool.

A band or belt 20 may be attached in any suitable manner to the appliance for holding the latter in position under a corset or other undergarment and the undergarment will firmly maintain said appliance in place without discomfort to the wearer.

The appliance illustrated in Figs. 1 to 5 inclusive is one used for a hollow back, the hollow often being the result of some illness that causes a weakening of the muscles. In such a case the person usually becomes round or stoop shoul- 30 dered or the shoulder on the deformed side of the body will become lower than the other due to the weakened condition of the muscles both in the area of and contiguous to the deformity. In producing the appliance, a mold is made of the 35 recess by using plaster of Paris or other suitable substance and the back of said mold is shaped to correspond to the general contour of the person's back. The plates are next made over the mold and connected to each other as previously 40 described. When the appliance is placed in position, it will fill the hollow or recess in the person's back and support the surrounding body structure so the person can stand erect and the body will have the correct appearance of sym- 45 metry.

In that form of the appliance illustrated in Figs. 6, 7 and 8 which is particularly adapted for use as a ptosis pad or abdominal support, the plates are of generally circular shape in plan and 50 the inner plate 10 has an elongated raised portion 21 extending from the edge of the appliance inward a desired distance, preferably beyond the center thereof, and partially surrounded by a depressed area which forms a substantially cres- 55 cent shaped channel 22. When such an appliance is pressed against the abdomen the channel forms a pocket and receives portions of the body which will hold said appliance practically immovable in the proper locality for effectively 60 supporting a fallen stomach in a manner that is comfortable to the wearer. Like the previously described appliance this one may be held in place by a belt or band, an undergarment or any other suitable means.

An appliance of the character described when made of a plastic composition as set forth herein assures a much lighter and cooler support than the average device for this purpose now on the market.

Of course I do not wish to be limited to the exact details of construction and the combination of all of the elements herein shown and described as these are merely illustrative and can be 70 varied within the limits of the appended claims.

without departing from the spirit and scope of the invention.

Having thus described my invention what I claim as new and useful is;—

1. In an orthopedic appliance, a hollow pad 5 consisting of inner and outer plates of hardened plastic composition previously fashioned to shape, one of said plates being slightly smaller than the other and provided with a roughened edge, hardened plastic composition fastening the edges 10 of said plates together, cork stays between the plates within the pad, means to hold said stays in position, and means passing through both plates for additionally securing them.

2. The structure in claim 1 wherein the means 15 for additionally securing the plates are rivets resulting from hardened plastic composition and including countersunk heads and a bulged shank.

3. In an orthopedic appliance, a hollow pad 20 consisting of perforated inner and outer plates of hardened plastic composition, the inner plate including an elongated raised portion extending from a part of its edge inward to a position in the locality of the center of the plate and a crescent shaped channel partially surrounding said 25 raised portion, said outer plate fashioned to the general shape of a person's body in the region where the pad is to be used, a joint of hardened plastic composition securing the edges of said plates together, rivets of hardened plastic composition to additionally fasten said plates, cork stays between the plates and within the pad, and bonds of hardened plastic composition to fix the 30 stays to said plates.

4. The method of making an orthopedic ap- 35 pliance of the character described which consists of making plates from sheets of plastic composition, then securing the plates together along their edges with cork stays between them, next inserting cylindrical sections of the plastic com- 40 position through countersunk holes in both plates and pressing said sections endwise to force some of the composition into said countersunk holes and bulge the material between the plates, then allowing the whole structure to harden and set, 45 and finally perforating the plates to provide vents.

5. In an orthopedic appliance, a hollow pad 50 consisting of inner and outer plates of hardened plastic composition, said inner plate fashioned to conform to a body deformity, and said outer plate shaped similar to the natural body in the region of the deformity, and means to fasten the edges of said plates together.

6. In an orthopedic appliance, a hollow pad 55 consisting of unyielding inner and outer plates of hardened plastic composition, said inner plate fashioned to conform to a body deformity to function as a support and said outer plate shaped similar to the natural body in the region of the 60 deformity, means to fasten the edges of said plates together, and stays between the plates and within the pad.

7. In an orthopedic appliance, a hollow pad 65 consisting of inner and outer plates of hardened plastic composition previously fashioned to shape, and means to secure said plates together along their edges.

8. In an orthopedic appliance, a hollow pad 70 consisting of inner and outer plates of hardened plastic composition previously fashioned to shape, means to secure said plates together, and means positioned within the pad between the plates for bracing said plates.
